N. J., a corporation of New Jersey

Application April 7, 1950, Serial No. 154,523

14 Claims. (Cl. 282—5)

1

This invention relates to locked copy ticket writers of the portable type, wherein sales can be noted on a sales ticket positioned on the outer surface of the device and a carbon copy of the sales made on a strip or sheet, which is automatically wound upon a receiving reel in the operation of feeding a new copy sheet into position in the device and in automatically effecting a successive sales slip or ticket from the device. More particularly, the invention deals with a device of the character described having an automatic control for definitely positioning the locked copy sheet with respect to the writing area of the device and a sales ticket disposed over said area.

The novel features of the invention will be best understood from the following description, when taken together with the accompanying drawings, in which, certain embodiments of the invention are disclosed and, in which, the separate parts are designated by suitable reference characters in each of the views and, in which:

Fig. 1 is a perspective view of a locked copy writer device made according to my invention.

Fig. 2 is a longitudinal sectional plan view of the device on an enlarged scale with parts of the construction broken away and omitted.

Fig. 3 is a section substantially on the line 3—3 of Fig. 2 on an enlarged scale and with parts of the construction broken away.

Fig. 4 is a partial section on the line 4—4 of Fig. 3.

Fig. 5 is a broken section on the line 5—5 of Fig. 2 on an enlarged scale.

Fig. 6 is a partial section on the line 6—6 of Fig. 5.

Fig. 7 is a perspective view of one end and side portion of the device omitting the outer casing and omitting the sales tickets.

Fig. 8 is a view similar to Fig. 3 showing only part of the construction on an enlarged scale with parts broken away and with parts in a different position.

Fig. 9 is a section on the line 9—9 of Fig. 8; and

Fig. 10 is a perspective detail view illustrating sheet flexure by the control arm of the device.

Considering Fig. 1 of the drawing, I have shown a locked copy ticket writer 15 comprising an elongated thin casing, the top wall of which has a large rectangular opening 16, said wall adjacent the opening having a pair of key pins 17 for positioning sales tickets 18, one at a time thereon, in the operation of recording sales. The top wall of the casing, adjacent the upper end

thereof, is bevelled, as seen at 19, to a contracted discharge end 20, whereas the other end of the casing is rounded, as seen at 21. Pivoted to the sides of the contracted end 20 is a handle member 22 which can be folded onto the lower surface of the casing, when not in use.

One side wall 23 of the casing has an elongated slot 24, in which an outwardly protruding fingerpiece or hand-grip 25 passes and operates, as later described.

Considering now Fig. 3 of the drawing, at 26 is shown the bottom wall of the casing which has a large opening extending from the upper contracted end 20 to a point adjacent the ends of tickets 18 supported in the casing and this opening is controlled by a cover 27 hinged, as seen at 28, the cover having suitable key lock mechanism, not shown, for retaining the same in closed position. The bottom wall 26 and cover 27 have supporting feet, as at 29, of suitable cushioning material for arranging the device, when not in use, on a table, counter or other support.

Supported beneath the opening 16 is a thin strip or sheet of suitable carbon or transfer material 30 which is held in position by bordering strips, part of which are seen at 31 in Fig. 3 of the drawing. Arranged below the sheet 30 is a table or platform 32, over which the locked copy strip or sheet 33 passes. The strip is disposed beneath the transfer sheet 30, as will be apparent.

At the upper portion of the casing is a compartment, the bottom wall of which is indicated at 34 in Fig. 3 of the drawing and, in this compartment and supported upon the wall 34, is a folded stack of the more or less endless sheet 33, as partially seen at 33' in Fig. 3.

The end of the sheet is threaded through the machine by passing downwardly over a rounded upwardly protruding portion 35 of the wall 34 near the top of the device and then around a drum or large roller 36, from which the strip 33 passes upwardly onto the table or platform 32. Considering Fig. 3, it will be noted that the upper end of this platform is depressed and slightly rounded, as seen at 32'.

The strip 33 then passes over a rounded portion 37 near the lower portion of the casing and, thus, onto the core 38 of a spool 39, note in this connection Fig. 5 of the drawing. The spool 39 constitutes the direct medium of winding of the strip 33. The spool has an axis portion 40 rotatably supported in the casing 15, as seen at 41. The axis 40 includes a friction drive disc 42 having a plurality of friction beds, as at 43, the disc

and axis supporting a sprocket 44 actuated by a ball chain drive 45, part of this chain being more clearly illustrated in Fig. 8 of the drawing.

The chain 45 also passes around another sprocket 46 disposed at one end of the drum 36, the drum having a suitable support in side frame plates of the device. These plates are shown at 47 and 48 in Fig. 2 of the drawing. An offset extension of the plate 47 is shown at 47' in Fig. 6, and also seen in Fig. 2, and a similar offset of the frame 48 is seen at 48' in Fig. 2 and in section in Fig. 5.

Considering Fig. 4 of the drawing, it will appear that the sprocket 46 is secured to the outer end of a trunnion or shaft portion 49 on the drum 36 and inwardly of the sprocket is a friction disc 50 and a ratchet 51. The ratchet 51 is indicated clearly in Fig. 8 of the drawing.

Secured to the frame 48 and extending longitudinally thereof is a channel rail 52, note Figs. 7 and 9. Mounted upon and movable longitudinally of this rail is a slide carriage 53. The carriage has a housing portion 54 terminating at its upper end in a pair of hook-shaped flanges 55 which operate in the upper channel 56 formed by the rail 52, as clearly seen. The lower portion 57 of the carriage bears against the face of the rail, as illustrated clearly in Fig. 9 of the drawing. The fingerpiece or hand-grip 25 is secured to the slide or carriage 53, as at 25', clearly noted in Fig. 7.

The carriage or slide has, at the lower portion 57 thereof, an upwardly directed extension 58 having, on the upper surface thereof, teeth forming a rack 59, note Fig. 7. Supported on the extension 58 and extending slightly beyond the rack 59 is an upwardly curved spring finger 60. The housing portion 54 of the slide or carriage 53 also has, near its outer portion, an upwardly extending bevelled trip-finger 61. At this time, it might be well to say that the terms "upwardly" and otherwise are associated with respect to what is termed the upwardly contracted end 20 of the casing.

Supported in the housing 54 of the carriage 53 is an axis 62 supporting a clutch disc 63 having a series of recesses in the periphery thereof, one of which is shown at 64 in Fig. 8 of the drawing. One wall 65 of this recess is slightly bevelled to facilitate jamming of a clutch ball 66 against a sprocket 67 in utilizing the sprocket as a means to feed or drive the chain 45.

The ball 66 operates against a U-shaped spring 68 in the recess 64 in freeing the sprocket so as to rotate freely around the clutch disc 63. In other words, when the finger-grip is moved from its extreme upper position, as seen in Fig. 1 of the drawing to the lowered position in the slot, the clutch 63 jams or locks the sprocket 67 to establish a definite coupling engagement with the chain 45, thus serving to draw the chain in the direction mentioned and rotate the spool 39 to wind the strip 33 thereon and, at the same time, to rotate the drum 36.

In the aforesaid stroke motion of the finger-piece 25, should the operator fail to complete the stroke and return the fingerpiece 25 to the upper position, as shown in Fig. 1 then, in this operation, the sprocket 67 is free to rotate and feed itself along the chain, which isn't moved. The operator will then realize the necessity of feeding the strip 33 a greater depth and will again move the fingerpiece in the downward direction through the drive of the chain until a control finger 69, constituting part of a long arm 70, has

passed over the T-crosshead portion 71 of a slit in the strip 33. The other portion 72 of the T-slit allows the finger 69 to drop downwardly, flexing the portions 73 of the sheet 33 in this operation in the manner indicated diagrammatically in Fig. 10 of the drawing. This operation takes place when the edge 69' of the finger registers with the crosshead 71. The finger 69 of the arm 70 is held in light tensional engagement with the strip 33 at all times by a spring 74, note Fig. 8, one end of the spring being secured to the casing and the other end to a pin 75 which operates in an elongated slot 76 in a pawl 77. The arm 70 and pawl 77 are both swingably mounted on a common pivot 78. A spring 79 operates to hold the pawl in a depressed position. However, it will appear that the finger 69 supported by the sheet 33 holds the pawl in raised inoperative position with respect to the ratchet 51, as seen in Fig. 3 of the drawing.

The finger 69 is arranged on an upwardly, as well as angularly offset portion 70' of the arm 70 and, adjacent the offset portion is an outwardly extending trip plate 80, which plate is adapted to be engaged by the trip extension 61 on the slide or carriage 53 to move the arm 70 into raised position, in other words, assuming that the arm 70 has dropped to lower the finger 69, thus allowing the pawl 77 to drop into operation engagement with the ratchet 51, as seen in Fig. 8. This then locks the ratchet against any further feed motion of the chain 45 or the strip 33. However, the fingerpiece 25 is then moved upwardly in the slot 24, returning the same to the position shown in Fig. 1, in which operation, the ratchet 67 rotates freely around the clutch 63 and rides along the chain and this operation continues until the trip 61 moves the arm 70 and pawl 77 into raised position, as shown in Fig. 3.

During the aforesaid return stroke motion of the carriage 53 by the fingerpiece 25, the rack 59 operates to rotate a pinion 81 at one end of a shaft 82, on which are arranged a pair of spiked discs 82' which operate as feed discs for feeding the uppermost ticket 18 in a pile to deliver or feed the same through a discharge slit 83 at the top of the device. Suitable tension means, not shown, will maintain an uppermost ticket of the pile in position to be engaged by said spiked discs. At the end of the shaft 82 is a clutch 84, generally similar to the clutch 63 for providing the direct feed drive of the roller 82 only as and when the pinion 81 is driven by the rack 59. The spring finger 60 provided on the rack is simply to engage the pinion to positively set the teeth for proper meshing with the first tooth of the rack should one of the teeth of the pinion be in a non-meshing alignment. It will be apparent that the operation of the rollers 82 takes place only as and when the rack establishes a driving engagement with the pinion 81 and on completing the stroke which is sufficient to project one of the tickets 18 sufficiently to be grasped by the hand; then in the reverse motion of the rack 59, the pinion 81 will be rotated but the shaft 82 and spiked discs 82' will remain idle, the clutch being then in an inoperative position.

Returning now to the lower end of the casing and the spool mounting, it will appear that another axis support 85 is provided for the spool 39, this axis being supported by a spring arm 86, note Figs. 2, 5 and 7, the axis 85 passing freely through an aperture 87 in the frame extension 47'. The spring arm 86 is held in operative position by a swinging yoke or retaining member 88,

rotatable on the axis 85, the member 88 having a pair of fingers 89 adapted to span the frame 47 and the spring arm 86 in maintaining the axis 85 in a position to properly support the spool 39. However, when the top of the casing is removed by suitable control means, which is not shown, and access to the spool is obtained, after the cover 27 has been moved into open position, the member 88 can simply be rotated and a cam portion 90 on said member will operate on an offset portion 91 on the spring finger and move and support the spring finger in inoperative position while at the same time disengaging the retaining fingers 89 from the spring. Then the spool 39 can freely be removed from the casing.

The above operation takes place as and when it is necessary for removal of the locked copy strip or sheet 33.

The spool 39 is of a two-part construction, as more clearly described in a companion application, filed of equal date herewith, and by separating the separate parts of the spool, the cylinder of wound strip 33 can easily be removed, whereupon the spool may be reassembled and placed in the device, preparatory to the winding of another strip, similar to the strip 33 thereon.

It will be apparent that the T-slits 11-12 are positioned on the strip 33 at measured spaced intervals so as to properly position a length of the strip beneath the opening 16 for recording of sales written on a ticket 18 disposed over said opening. The table or platform portion 32, or its extension 32', has an aperture 92 therein, note Figs. 2 and 10, one end wall of this aperture having bevelled wall portions, as at 93, and the finger 69 is adapted to drop into the aperture 92 as and when the crosshead portion 71 of the slit reaches the position, just beyond the bevelled walls 93, as at 94, note Fig. 2. This position is also indicated in Fig. 10 of the drawing. The bevelled walls 93 serve to feed the depressed portions 73 of the strip 33 upwardly in the next successive feed of said strip. A pair of rubber rollers 95 are supported on a swinging rod 96 and are adapted to hold the strip 33 against the drum 36, as indicated in Fig. 2, and a spring 97 engages the arm 96 to hold the rollers 95 in operative position.

From the foregoing, it will be apparent that, in the normal feed motion of the strip 33 through the medium of the chain drive actuated through the carriage or slide 53 having the fingerpiece 25, the strip is wound upon the spool 39 and a new section of the strip is positioned beneath the opening 16. This position is controlled by the dropping of the finger 69 into the aperture 92 as and when the crosshead 71 of a new slit approaches the position previously mentioned. Then the carriage is moved upwardly, which operation effects one of the tickets 18 which is stripped from the machine by hand, then placed over the pin 17 and a new sales recorded. After the sales have been recorded, this ticket is removed and the above operation is again repeated to bring a new section of the strip 13 into position, the previous section with the recorded sales thereon having been wound upon or, at least for the most part, the spool 39.

Having fully described my invention, what I claim as new and desire to secure by Letters Patent is:

1. A device of the character described, comprising a casing, having a rectangular opening in one wall thereof, with means on said wall for supporting a ticket over said opening, a platform in the casing beneath said opening, over which a

copy sheet is adapted to be moved, means for supporting an elongated copy sheet in folded position in the casing beneath said platform, a spool rotatably supported in one end of the casing and on which said sheet is adapted to be wound, a drum rotatably supported in the other end of the casing, said spool and drum having sprocket ends over which a chain is adapted to pass, one side wall of the casing having an elongated aperture, a rail extending longitudinally of the casing inwardly of said aperture, a slide movable longitudinally of the rail and having a fingerpiece portion extending through said aperture, a clutch sprocket mounted on and movable with said slide and operatively engaging the chain in positive feed of the chain in one direction to wind said sheet on said spool, and the clutch of said last named sprocket facilitating free movement of the slide longitudinally of the chain in the opposite direction.

2. A device of the character described, comprising a casing, having a rectangular opening in one wall thereof, with means on said wall for supporting a ticket over said opening, a platform in the casing beneath said opening, over which a copy sheet is adapted to be moved, means for supporting an elongated copy sheet in folded position in the casing beneath said platform, a spool rotatably supported in one end of the casing and on which said sheet is adapted to be wound, a drum rotatably supported in the other end of the casing, said spool and drum having sprocket ends over which a chain is adapted to pass, one side wall of the casing having an elongated aperture, a rail extending longitudinally of the casing inwardly of said aperture, a slide movable longitudinally of the rail and having a fingerpiece portion extending through said aperture, a clutch sprocket mounted on and movable with said slide and operatively engaging the chain in positive feed of the chain in one direction to wind said sheet on said spool, the clutch of said last named sprocket facilitating free movement of the slide longitudinally of the chain in the opposite direction, said sheet having, at predetermined spaced intervals, slits, and means comprising a tensioned finger engaging said sheet in alignment with the slits therein for controlling free movement of said slide upon the finger engaging a slit in said sheet.

3. A device of the character described, comprising a casing, having a rectangular opening in one wall thereof, with means on said wall for supporting a ticket over said opening, a platform in the casing beneath said opening, over which a copy sheet is adapted to be moved, means for supporting an elongated copy sheet in folded position in the casing beneath said platform, a spool rotatably supported in one end of the casing and on which said sheet is adapted to be wound, a drum rotatably supported in the other end of the casing, said spool and drum having sprocket ends over which a chain is adapted to pass, one side wall of the casing having an elongated aperture, a rail extending longitudinally of the casing inwardly of said aperture, a slide movable longitudinally of the rail and having a fingerpiece portion extending through said aperture, a clutch sprocket mounted on and movable with said slide and operatively engaging the chain in positive feed of the chain in one direction to wind said sheet on said spool, the clutch of said last named sprocket facilitating free movement of the slide longitudinally of the chain in the opposite direction, said sheet having, at

predetermined spaced intervals, slits, means comprising a tensioned finger engaging said sheet in alinement with the slits therein for controlling free movement of said slide upon the finger engaging a slit in said sheet, and said last named means including a pawl and ratchet structure at one end of said drum and adapted to check rotation of the drum in one direction.

4. In a device of the character described employing a copy sheet on which sales are adapted to be recorded, a casing, means comprising a spool at one end of the casing for winding said sheet in storage of recorded sections thereon, a chain and sprocket structure for rotating said spool, a slide mounted for movement longitudinally of the casing, said slide having a rack portion, the slide having a fingerpiece portion protruding through the casing, means comprising a clutch ratchet on said slide for engaging the chain in feed of said chain in one direction to rotate said spool, said casing storing sales tickets, rotatable ticket ejector means, and means actuated by the rack portion of said slide for operating said ticket ejecting means to eject one of the tickets from the storage through one end of said casing.

5. In a device of the character described employing a copy sheet on which sales are adapted to be recorded, a casing, means comprising a spool at one end of the casing for winding said sheet in storage of recorded sections thereon, a chain and sprocket structure for rotating said spool, a slide mounted for movement longitudinally of the casing, said slide having a rack portion, the slide having a fingerpiece portion protruding through the casing, means comprising a clutch ratchet on said slide for engaging the chain in feed of said chain in one direction to rotate said spool, said casing storing sales tickets, rotatable ticket ejector means, and means actuated by the rack portion of said slide for operating said ticket ejecting means to eject one of the tickets from the storage through one end of said casing, and means comprising a pawl and ratchet for feed movement of the chain in said first named direction.

6. In a device of the character described employing a copy sheet on which sales are adapted to be recorded, a casing, means comprising a spool at one end of the casing for winding said sheet in storage of recorded sections thereon, a chain and sprocket structure for rotating said spool, a slide mounted for movement longitudinally of the casing, said slide having a rack portion, the slide having a finger piece portion protruding through the casing, means comprising a clutch ratchet on said slide for engaging the chain in feed of said chain in one direction to rotate said spool, said casing storing sales tickets, rotatable ticket ejector means, and means actuated by the rack portion of said slide for operating said ticket ejecting means to eject one of the tickets from the storage through one end of said casing, means comprising a pawl and ratchet for feed movement of the chain in said first named direction, and means comprising a spring actuated finger operatively engaging said sheet controlling movement of said pawl into operative position.

7. In a device of the character described, employing a copy sheet on which sales are adapted to be recorded, a casing, means comprising a spool at one end of the casing for winding said sheet in storage of recorded sections thereon, a chain and sprocket structure for rotating said spool, a slide mounted for movement longitudinally of the casing, said slide having a rack portion, the slide

having a fingerpiece portion protruding through the casing, means comprising a clutch ratchet on said slide for engaging the chain in feed of said chain in one direction to rotate said spool, said casing storing sales tickets, rotatable ticket ejector means, means actuated by the rack portion of said slide for operating said ticket ejecting means to eject one of the tickets from the storage through one end of said casing, means comprising a pawl and ratchet for feed movement of the chain in said first named direction, means comprising a spring actuated finger operatively engaging said sheet controlling movement of said pawl into operative position, and means on said carriage engaging said finger to move said pawl into inoperative position.

10 8. In locked copy writers of the character described employing an elongated copy sheet arranged in a casing, a spool at one end of the casing for winding the sheet, means for intermittently feeding the sheet and winding the same on said spool, said sheet having longitudinally spaced slits, a spring control finger engaging the sheet in alinement with said slits, a pawl and ratchet for checking winding movement of said sheet on the spool, said finger normally supporting the pawl in inoperative position, and said finger releasing the pawl for movement into operative position upon engagement of the finger with a slit in said sheet.

20 9. In locked copy writers of the character described employing an elongated copy sheet arranged in a casing, a spool at one end of the casing for winding the sheet, means for intermittently feeding the sheet and winding the same on said spool, said sheet having longitudinally spaced slits, a spring control finger engaging the sheet in alinement with said slits, a pawl and ratchet for checking winding movement of said sheet on the spool, said finger normally supporting the pawl in inoperative position, said finger releasing the pawl for movement into operative position upon engagement of the finger with a slit in said sheet, and said sheet feed means having means for moving said pawl into inoperative position in one directional movement of said feed means.

30 10. In locked copy writers of the character described employing an elongated copy sheet arranged in a casing, a spool at one end of the casing for winding the sheet, means for intermittently feeding the sheet and winding the same on said spool, said sheet having longitudinally spaced slits, a spring control finger engaging the sheet in alinement with said slits, a pawl and ratchet for checking winding movement of said sheet on the spool, said finger normally supporting the pawl in inoperative position, said finger releasing the pawl for movement into operative position upon engagement of the finger with a slit in said sheet, and said first named means including means for moving said pawl into inoperative position.

40 11. In locked copy writers of the character described employing an elongated copy sheet arranged in a casing, a spool at one end of the casing for winding the sheet, means for intermittently feeding the sheet and winding the same on said spool, said sheet having longitudinally spaced slits, a spring control finger engaging the sheet in alinement with said slits, a pawl and ratchet for checking winding movement of said sheet on the spool, said finger normally supporting the pawl in inoperative position, said finger releasing the pawl for movement into

operative position upon engagement of the finger with a slit in said sheet, means for storing tickets in the casing, and means actuated by said first named means for discharging tickets one at a time from said casing.

12. In locked copy writers of the character described employing an elongated copy sheet arranged in a casing, a spool at one end of the casing for winding the sheet, means for intermittently feeding the sheet and winding the same on said spool, said sheet having longitudinally spaced slits, a spring control finger engaging the sheet in alignment with said slits, a pawl and ratchet for checking winding movement of said sheet on the spool, said finger normally supporting the pawl in inoperative position, said finger releasing the pawl for movement into operative position upon engagement of the finger with a slit in said sheet, means for storing tickets in the casing, means actuated by said first named means for discharging tickets one at a time from said casing, said last named means comprising a rack on the first named means, a pinion driven by said rack, and a ticket gripping and feed disc and a clutch controlling rotation of said disc in one direction.

13. In ticket writers of the character described, a casing in which a locked copy sheet is adapted to be arranged, a spool at one end of the casing on which the sheet with recordings thereon is adapted to be wound, said spool having pivot axes at the ends thereof, one pivot axis

including a friction disc, means in the casing for driving said disc, the other pivot axis being yieldably supported in the casing facilitating attachment and detachment of the spool, and means rotatable about the last named axis for clamping said axis in operative position.

14. In ticket writers of the character described, a casing in which a locked copy sheet is adapted to be arranged, a spool at one end of the casing on which the sheet with recordings thereon is adapted to be wound, said spool having pivot axes at the ends thereof, one pivot axis including a friction disc, means in the casing for driving said disc, the other pivot axis being yieldably supported in the casing facilitating attachment and detachment of the spool, means rotatable about the last named axis for clamping said axis in operative position, and said clamping means having means for moving 20 and supporting said axes in inoperative position.
